BOLT LOCK FOR A RIFLE

Claude Alfred Perry, Olton, and Roger David Wackrow, Handsworth, England, assignors to The Birmingham Small Arms Company Limited, Small Heath, Birmingham, England

Application February 19, 1954, Serial No. 411,524

4 Claims. (Cl. 42—16)

This invention is concerned with improvements in or relating to bolt-action rifles, and is particularly concerned with the provision of safety mechanism therefor.

Safety mechanism of bolt-action rifles is usually of a two-fold character. When it is desired to render the weapon inoperative, movement of the safety-catch locks the striker (usually by locking the cocking piece) and also locks the bolt. The principal feature of the present invention is directed to an improved way of locking the striker.

According to this invention a bolt-action rifle includes a two-part hollow bolt, the two parts being rotatably secured together, and a cam mounted on the rearward part of the bolt for rotation about a horizontal transverse axis, the cam being so located as to be capable of engaging a groove in a cocking piece when the bolt is in cocked position, thereby to prevent forward movement of the striker.

According to a feature of the invention, the cam is located in the lower half of the rearward part of the bolt, the upper part of which is arcuate shaped to provide a track for the thumb piece for operating the cam.

According to a further feature of the invention, the cam causes rearward movement of the cocking piece, thereby to remove the cocking piece substantially from engagement with the sear when in cocked, but safe, position.

According to yet another feature of the invention, movement of the cam effects movement of an auxiliary member to lock the forward part of the bolt against rotation when the rifle is in safe position.

One construction in accordance with the invention will now be particularly described with reference to the accompanying drawings in which:

Fig. 1 is a sectional view through a bolt action rifle trigger mechanism;

Fig. 2 is a view of part of the mechanism shown in Fig. 1 with the safety catch in a different position;

Fig. 3 is a side view of part of a rifle from the other side;

Fig. 4 is a side view of a cocking piece;

Fig. 5 is a section through the cocking piece taken on line 5—5 in Fig. 4;

Fig. 6 is a view of the rear portion of the bolt from underneath;

Fig. 7 is a sectional side view of the rear portion of the bolt;

Fig. 8 is a side view of the cam shaft;

Fig. 9 is a front view of the cam shaft;

Fig. 10 is a section on the line 10—10 in Fig. 9;

Fig. 11 is a section on the line 11—11 in Fig. 9;

Fig. 12 is a section through the rear portion of the bolt and the cocking piece with the cam shown in full.

A bolt-action rifle according to this particular construction is provided with a two-part hollow bolt, the rear part 1 thereof being screw-threaded into the forward part 2 thereof. A firing pin 5 and a cocking piece 7 are located within the bolt and a striker spring 9 is disposed

2

between the forward end of the rear part of the bolt and a projection 13 on the firing pin. The rear end portion of the cocking piece 7 is provided with a depending portion 3 which not only acts as a shoulder for abutting against a sear 21 when the bolt is in cocked position, but also acts so as to prevent rotation of the rear part of the bolt. Consequently, when it is desired to cock the rifle, the forward part 2 of the bolt is rotated with respect to the rearward part 1 and the whole moved rearwardly.

10 The rearward part of the bolt is provided in its lower half with a transversely-extending hole 15 within which a cam shaft 17 is located. This cam shaft forms part of a safety catch 19 and may be rotated by a thumb piece 10 at the side of the rearward part of the bolt. The rear upper portion 11 of this part of the bolt is arcuate in profile and is chamfered and thus provides a track over which the thumb piece 10 may move. Normally the cam shaft 17 allows free movement of the cocking piece during movement of the bolt in order to cock the rifle (as illustrated in Fig. 1), but rotation of the cam shaft when the bolt and cocking piece are in cocked position allows the cam portion 17 of the shaft to enter into a groove 15a in the cocking piece. At the same time the cam portion of the cam shaft engages the shoulder 3 formed by the rear wall of the groove 15a and causes the cocking portion 3 of the cocking piece 7 to move rearwardly from its cocked position for only a short distance. The distance is, however, sufficient to remove the shoulder 23 of the cocking piece away from the sear 21, thereby not only to prevent unnecessary pressure on the sear, but also to allow the sear to ride upwardly under the influence of a spring urged lever 24 until it lies within a narrow groove 25 formed in the rear end of the forward part of the bolt. The engagement of the sear with this groove prevents rotation of the forward part of the bolt when the rifle is in cocked position with the safety catch applied.

15 By mounting the cam shaft 17 so that its axis is in the lower half of the rearward part of the bolt, it is possible to use a low-mounted telescopic sight without interference from the thumb piece 19 which operates the cam shaft. At the same time, by providing an arcuate chamfered track for the thumb piece there is little likelihood of the thumb piece accidentally being moved from one of its positions to the other.

20 A spring loaded plunger 27 mounted in a hole 31 in the rear portion 1 of the bolt is adapted to engage a slot 29 formed in part of the safety catch 19 whereby the safety catch is retained in the firing position.

Having thus described our invention, what we claim as new and desire to secure by Letters Patent is:

25 1. A bolt action rifle comprising a hollow bolt composed of forward and rear parts rotatably secured together, a sear, a cocking piece therefor provided with a depending portion reciprocable within the bolt and having a groove extending transversely in its rear portion and a shoulder rearwardly of said groove, and a safety catch having a cam thereon and located in the lower half of the rear part of the bolt for rotation about a horizontal transverse axis, the catch including a thumb-piece and the cam being rotatable by said thumb-piece into a position to aline with the groove in the cocking piece to permit cocking of the cocking piece while the bolt is in cocked position, and rotatable into another position to abut against said shoulder and thereby prevent forward movement of the cocking piece.

30 2. A bolt action rifle as defined in claim 1, wherein the upper surface of the rear part of the bolt is arcuate about the axis of the cam to provide a track over which the thumb-piece of the catch moves for rotating the cam.

35 3. A bolt action rifle as defined in claim 1, wherein the cam actuated by the catch causes rearward movement of the cocking piece, thereby to move and hold the cock-

ing piece from engagement with the sear when in the cocked, but safe, position.

4. A bolt action rifle as defined in claim 1 wherein the forward part of the bolt is provided with a narrow groove, and including a spring-loaded lever operative, when the sear is freed from engagement by the sear, to cause the sear to ride upwardly and engage said narrow groove in the bolt, thereby preventing rotation of the forward part of the bolt when the rifle is in cocked position with the safety catch applied.
